(57) CLAIM

The ornamental design for a modular planter, as shown and described.

DESCRIPTION

FIG. 1 is a front perspective view of a first embodiment of the modular planter showing my new design.

FIG. 2 is a front view thereof;

FIG. 3 is a right side view thereof, the undisclosed left side view being a mirror image;

FIG. 4 is a top view thereof;

FIG. 5 is a bottom view thereof; and,

FIG. 6 is a front perspective view of a second embodiment of the modular planter, to indicate that modules can be inserted to increase the length of the modular planter.

The broken lines showing drainage openings in FIGS. 4, 5, are for illustrative purposes only and form no part of the claimed design.
